CLAIM

The ornamental design for a honeycomb sheet for steering wheel wrap, as shown and described.

DESCRIPTION

FIG. 1 is a perspective view of a honeycomb sheet for steering wheel wrap, in accordance with the present invention;

FIG. 2 is a front elevation view of the honeycomb sheet for steering wheel wrap, in accordance with the present invention;

FIG. 3 is a top plan view of the honeycomb sheet for steering wheel wrap, in accordance with the present invention;

FIG. 4 is a right side elevation view of the honeycomb sheet for steering wheel wrap, in accordance with the present invention;

FIG. 5 is a rear elevation view of the honeycomb sheet for steering wheel wrap, in accordance with the present invention;

FIG. 6 is a bottom plan view of the honeycomb sheet for steering wheel wrap, in accordance with the present invention; and,

FIG. 7 is a left side elevation view of the honeycomb sheet for steering wheel wrap, in accordance with the present invention.

In the drawings, the broken lines indicate the boundaries of the claimed design. The broken lines form no part of the claimed design.
